CABINET FOR ELECTRONIC APPARATUS

Roy A. Ozaki, Sunnyvale, Calif., assignor to Hewlett-Packard Company, Palo Alto, Calif., a corporation of California

Filed July 16, 1968, Ser. No. 12,786

Term of patent 14 years

Int. Cl. D14—02; D18—01

U.S. Cl. D26—5

Figure 1

Figure 2

FIGURE 1 is a front perspective view of the cabinet for electronic apparatus, and

FIGURE 2 is a rear perspective view of the cabinet of FIGURE 1.

The dominant features of the invention are shown in solid lines.

The broken line illustration of the control buttons and switches are shown for illustrative purposes only.

I claim:

The ornamental design for a cabinet for electronic apparatus, as shown and described.
